UNITED STATES PATENT OFFICE.

GEORGE C. GILLESPIE, OF GREAT KILLS, AND FREDERICK W. BARKER, OF NEW DORP,
NEW YORK.

AIRPLANE.

1,359,590.

Specification of Letters Patent. Patented Nov. 23, 1920.

Application filed August 31, 1918. Serial No. 252,205.

To all whom it may concern:

Be it known that we, GEORGE C. GILLESPIE, a citizen of the United States, and FREDERICK W. BARKER, a subject of King George V of England, respectively, residents of Great Kills and New Dorp, both in the county of Richmond and State of New York, have invented certain new and useful Improvements in Airplanes, of which the following is a specification.

10 This invention relates to airplanes, and our improvement is particularly directed to braking or speed retarding means, as for nose dives or when falling, and whereby landings may be effected with greater safety than heretofore; also whereby an airplane may be brought to a halt after a relatively short surface run.

The high powered airplanes whose flying speed ranges from 100 to 150 miles an hour, and which in landing under favorable conditions touch the ground at from 50 to 90 miles an hour, require an even surfaced runway of from 300 to 500 feet to assure freedom from accidents. These surface conditions are not always available, especially when a forced landing has to be made, and it is desirable that the speed of the machine should be retarded, both when gliding toward the landing place, and when, under momentum, it is rolling along the surface.

Therefore our invention consists of pressure or braking vanes, normally closed against the sides of the fuselage, and adapted to be swung outwardly to present a large increase in drift or head resistance of the airplane, thereby causing a diminution in its speed of movement.

Two pairs of these braking vanes, all of the same area, may be employed, operating, respectively, at the opposite sides of the fuselage, and at the top and bottom thereof. Thus the increased pressure may be applied equally in lines of force exerted in parallelism with and about the longitudinal axis of the airplane, and thereby no tendency is created to vary the directional control of the machine.

Further, said braking vanes may be located rearwardly of the center of gravity of the machine, where they have the effect of stabilizing the machine in its controlled direction of movement.

Appreciating the necessity of minimizing the amount of energy required to be put

forth by the pilot in operating the braking vanes, to apply them, and also to assure their smooth and easy working, we have devised a sliding carriage, mounted within the fuselage, and operable through a lever under the control of the pilot; and a system of compound leverage between the sliding frame and the braking vanes, the latter being balanced or nearly balanced, whereby said vanes may be moved out or in with the exercise of relatively little effort by the pilot.

Other features and advantages of our invention will hereinafter appear.

In the drawings:—

Figure 1 is a plan view of a portion of a fuselage frame, broken away, and showing our improvement.

Fig. 2 is a perspective view of the rearward portion of a fuselage, with the braking vanes extended therefrom.

Fig. 3 is a cross-sectional view of the fuselage frame, having the guide brackets for the sliding carriage.

Fig. 4 is a detail showing the cockpit portion of the fuselage, having an operating lever mounted therein, and Fig. 5 is a detail perspective view showing the relative connected arrangement of the braking vanes.

In carrying out our invention we provide means whereby the pressure vanes, located respectively at the top, bottom and sides of the fuselage, are pivotally mounted upon a single carriage or frame which is adapted to slide longitudinally within the fuselage, the engaging fulcrum between the vanes and carriage being thus movable. A separate guide arm for each vane is pivoted thereto, at an outward portion thereof, and also has fixed pivotal engagement with the fuselage, to thus cause the vane to turn out or in concurrently with the rearward or forward sliding movements of the carriage.

In the drawings we have shown an airplane fuselage whose frame is composed of the longerons 1 and transverse members 2. Mounted in the angles of said frame are brackets 3, having guide orifices 4, to receive slidable rods 5, which latter comprise the longitudinal members of the vane operating carriage or frame. In the present example of our invention, wherein the fuselage is shown as equipped with four pressure vanes 6, four of the rods 5 are required, since each vane 6 is carried by a pair of rods 5.

The hinge portions of the vanes, as 7, 110

may each extend rearwardly from said vanes and extend through slots 8 in the fuselage covering, and engage with pintles 9 carried by a bushing 10 on a rod 5. Each bushing 10 may obviously have hinge connection for two right-angularly pivoted vanes 6, when four of said vanes are employed.

The slideable frame is produced by connecting the rods 5 with transverse rods 11, 10 and diagonally extended, crossed bracing rods 12, which latter may be connected, at their points of intersection 13, to comprise a strong and rigid structure.

Guide arms 14, of which a pair may be 15 used for each vane 6, are pivoted each at one end to a fixed point in the fuselage frame, as at 15, and, at their opposite ends are pivoted to said vanes, toward the outer portion of the latter, as at 16, to cause said 20 vanes to swing outwardly through a flattened arc during the rearward sliding movement of the carriage. It will be obvious that the pivoted connection 16 between arms 14 and a vane 6 should be located in the 25 most effective portion relatively to the chord of the vane, and we prefer to locate these pivotal points toward the outer edge, in order to attain a pressure balancing effect upon the vane for facilitating its outward 30 turning movement.

As the carriage is moved rearwardly the rods 5 carry with them the inner hinged portions of the vanes, and the vanes being held at their outward portions by arms 14, 35 thus swing outwardly to the desired braking positions.

The carriage may be actuated as by a lever 17, mounted in the cockpit, under the control of the pilot, and connecting by rod 18 40 with said carriage. A rack 19 or the like may be employed to hold the lever 17 in a desired operative position.

In order to absorb the shocks resulting 45 from the sudden impact of the sliding carriage upon reaching the limit of its movement, we provide cushions, as 20, which may be composed of cork or other resilient material. These cushions may be mounted upon the fuselage frame in positions to 50 serve as stops for the carriage at the limit of its movement in operating the vanes to their full extended opening.

Variations may be resorted to within the 55 spirit and scope of our invention, and parts thereof used without others.

We claim:—

1. Speed retarding means for airplanes comprising vanes normally closed against the four sides of the fuselage, and manually controlled means to synchronously extend said vanes for balanced pressure resistance offered in directions parallel to the longitudinal axis of the airplane, said vanes presenting their pressure surfaces at increasing, rearwardly outward inclinations 60 relatively to the longitudinal axis of the airplane, as said vanes are being extended.

2. The combination, with an airplane having a fuselage, of braking vanes normally closed against opposite sides thereof, 70 and having longitudinal slideable engagement with said fuselage, and means for turning said vanes outwardly, to offer pressure resistance surfaces in the line of flight, while said vanes are outward. 75

3. The combination, with an airplane, having a fuselage, of braking vanes movable from and to said fuselage, means slideable upon the fuselage to move said vanes longitudinally, and guide means to turn said 80 vanes outwardly, the guide means engaging the vanes in intermediate positions along their chords, whereby said vanes are pressure balanced in turning outwardly.

4. The combination, with an airplane, 85 having a fuselage, of braking vanes movable from and to said fuselage, means slideable upon the fuselage to move said vanes longitudinally, and guide means, in fixed pivotal engagement, respectively, with the 90 fuselage and said vanes, to accord outward turning movement to said vanes during their longitudinal motion.

5. The combination, with an airplane, having a fuselage, of a carriage slideably 95 mounted upon said fuselage, control means for said carriage, brake vanes mounted on said carriage, and means co-acting with said sliding carriage to turn said vanes outwardly or inwardly according to the direction of movement of said carriage. 100

Signed at the borough of Manhattan, in the city, county and State of New York this 30th day of August, A. D. 1918.

GEORGE C. GILLESPIE.
FREDERICK W. BARKER.
